(57) CLAIM

The ornamental design for a “vaporizer accessory organizer”, as shown and described.

DESCRIPTION

FIG. 1 is a top front perspective view of a vaporizer accessory organizer embodying the present design.

FIG. 2 is similar to FIG. 1 with the accessories removed.

FIG. 3 is similar to FIG. 2 with the detachable storage pouch also removed.

FIG. 4 is a rear perspective view thereof.

FIG. 5 is a top perspective view of the detachable storage pouch.

FIG. 6 is a bottom perspective view thereof.

FIG. 7 is a front elevation view of the vaporizer accessory organizer with the detachable storage pouch removed.

FIG. 8 is rear elevation view thereof.

FIG. 9 is a front elevation view thereof with the full length of the tie strap shown; and,

FIG. 10 is a perspective view thereof in a rolled-up position with the tie strap secured.

The dashed lines shown in the drawings depict stitching and forms part of the claimed design. The cutaway symbols illustrated in dot-dash break lines in FIGS. 1-4 and 7-10 indicate a symbolic break in the length of the strap indicating an indeterminate length. The appearance of any portion of the article between the break lines forms no part of the claimed design.

All other dot-dash broken lines shown in the drawings depict portions of the vaporizer accessory organizer and environment that form no part of the claimed design.
